UNITED STATES PATENT OFFICE.

ALEXANDER MARSCHALEK, OF EAST RUTHERFORD, NEW JERSEY.

AIR PUMP.

Application filed September 25, 1920. Serial No. 412,669.

To all whom it may concern:

Be it known that I, ALEXANDER MARSCHALEK, a subject of the King of Italy, and a resident of East Rutherford, in the county 5 of Bergen and State of New Jersey, have invented a new and Improved Air Pump, of which the following is a full, clear, and exact description.

The object of the invention is to provide 10 a new and improved air pump more especially designed for the use of autoists and other persons and arranged to enable the user to conveniently actuate the pump to quickly inflate the tires to a desired pressure 15 without requiring undue physical exertion.

Another object is to permit of temporarily attaching the air pump to the running board or other member of the automobile thus enabling the user to conveniently actuated 20 the air pump.

With these and other objects in view, the invention consists of certain novel features of construction as hereinafter shown and described and then specifically pointed out 25 in the claims.

A practical embodiment of the invention is represented in the accompanying drawings forming a part of this specification, in which similar characters of reference indicate corresponding parts in all the views. 30

Figure 1 is a plan view of the improved air pump with the operating handle shown in section;

Figure 2 is a front elevation of the same 35 with the air outlet omitted;

Figure 3 is an end elevation of the same; and

Figure 4 is an enlarged sectional plan view of one of the barrels and its mounting.

The improved air pump in its general construction is provided with two barrels or cylinders 10 and 11, of which the barrel 10 is provided with inner and outer heads 12 and 13, and similar heads 14 and 15 are arranged on the barrel 11. In the barrels are mounted to reciprocate plungers 20 and 21, provided with plunger rods 22, 23 extending through the inner heads 12 and 14 of the barrels 10 and 11. The outer ends of 45 the plunger rods 22 and 23 are connected by a pivot 24 with a handle 25, under the control of the user of the air pump, to reciprocate the plungers 20 and 21 in the barrels 10 and 11, and imparting a swinging motion 50 to the barrels 10 and 11 in the same plane, as hereinafter more fully explained.

The outer heads 13 and 15 of the barrels 10 and 11 are mounted to swing on the transverse ends 30 and 31 of a frame 32, and the said ends 30 and 31 are provided with 60 clamps 33 and 34 adapted to engage a running board 35 or other support for temporarily supporting the air pump while using the same. It will be noticed that by the arrangement described, the barrels 10 and 11 are mounted to swing up and down on the ends 30 and 31 of the supporting frame 32, the barrels swinging in the same plane. It will be noticed that when the barrels 10 and 11 have their axes coinciding then the 65 plungers 20 and 21 are in their outermost positions, and when the operator pulls the handle 25 upward then a desired swinging movement is given to the barrels 10 and 11, and the plungers 20 and 21 move inward 70 towards each other in the barrels 10 and 11. When the handle 25 is pushed downward then the barrels 10 and 11 are swung downward and the plungers 20 and 21 move outward in the said barrels 10 and 11. A like 75 movement is imparted to the barrels 10 and 11 and their plungers 20 and 21 on pushing the handle 25 downward and returning it after the barrels 10 and 11 have reached an aligned position with their axes coinciding. 80

The outer heads 13 and 15 of the barrels 10 and 11 are provided with valved outlets 40 and 41 connected by tubes 42, 43 with a T-shaped fixture 44 from which extends a tube 45 provided with a gage 46 and a coupling 47 for connecting the tube 45 with the valve of the tire to be inflated. 90

The operation is as follows:

When the pump is attached to the running board 35 of an automobile and the coupling 47 is connected with the valve of a tire to be inflated then the operator alternately moves the handle 25 up and down to impart corresponding swinging movements to the barrels 10 and 11 and to cause the 95 plungers 20 and 21 to reciprocate in the barrels 10 and 11. During the outer movement of the plungers 20 and 21 the air in the outer ends of the barrels 10 and 11 is pushed through the valved outlets 40 and 41 into 100 and through the tubes 42, 43, 44 and 45 to pass into the tire to be inflated to a desired pressure, indicated by the gage 46. The 105 plungers 20 and 21 are cushioned, on moving into innermost positions, by suitable springs 50 or other cushioning devices, thus preventing the user from moving the handle 25 too 110

far up or too far down. It is understood that the plungers 20 and 21 are of usual construction, and the inner heads 12 and 14 are provided with suitable air inlets 55 to allow air to pass into the inner ends of the barrels 10 and 11 to prevent the formation of a vacuum therein.

From the foregoing it will be seen that a double barrel pump is provided having but 10 a single handle for actuating the pumps to force a large amount of air into the tire in a comparatively short time and without requiring undue physical exertion on the part of the operator. The air pump shown and 15 described takes up comparatively little room and can be readily carried along in an automobile and quickly and conveniently attached to the running board whenever it is desired to inflate any one of the tires on the 20 corresponding side of the vehicle.

The air pump shown and described is very simple and durable in construction and is not liable to get easily out of order.

Having thus described my invention, I 25 claim as new and desire to secure by Letters Patent:—

1. An air pump, comprising a pair of barrels pivoted at their outer ends to swing up and down in the same plane, plungers 30 reciprocating in the barrels and having plunger rods extending through the inner ends of the barrels, valved outlets at the pivotal ends of the barrels, a manually operated handle pivotally connected with and 35 supported by the projecting ends of the plunger rods for simultaneously swinging the barrels up and down and reciprocating the plungers in the same direction, and a cushioning means for limiting the up and 40 down movement of the handle.

2. An air pump comprising a frame provided with means for attaching it to a support, a pair of barrels having closed ends, the outer ends of the barrels being mounted 45 on the frame to swing up and down, spring pressed plungers in the barrels and having plunger rods extending out through the inner ends of the barrels, valved outlets adjacent the pivotal ends of the barrels, and 50 a manually operated handle pivotally connected with and supported by the plunger rods for simultaneously swinging the barrels and reciprocating the plungers in the same direction.

3. An air pump, comprising a frame having inwardly extending members provided with clamps for attaching the frame to a support, barrels provided with inner and outer heads at the inner and outer ends of 60 the barrels, the outer heads being pivoted on the end members of the said frame, valved outlets mounted on the said outer

heads, plungers in the said barrels and having their plunger rods extending through the said inner heads, and a manually operated handle pivotally connected with the outer ends of the said plunger rods for simultaneously swinging the barrels up and down and reciprocating the pistons in the same direction.

4. An air pump comprising a rod having right angular ends provided with clamps for securing it to a support a pair of barrels having heads closing the same, the outer heads having horizontal openings 65 through which the angular ends of the rod pass and upon which ends the barrels swing, valved outlets at the pivotal ends of the barrels, plungers in the barrels and having plunger rods extending through the inner 70 heads of the barrels, and a manually operated handle pivotally connected with the projecting ends of the plunger rods.

5. In a device of the character described, a plurality of pumps supported for swinging movement and each having a cylinder and a piston, and means for simultaneously 75 swinging said pumps about their pivots and moving said pistons on their compression strokes.

6. In a device of the character described, a plurality of pumps supported for swinging movement and each having a cylinder and a reciprocating piston, and means for simultaneously swinging said pumps in opposite directions about their pivots and reciprocating said pistons within said cylinders.

7. In a device of the character described, a plurality of opposed pumps supported for 80 swinging movement and each having a cylinder and reciprocating piston, and operating means connected to said pistons and adapted to simultaneously swing said pumps towards each other about their pivots and 85 reciprocate said pistons within said cylinders.

8. In a device of the character described, a frame, a plurality of pumps each having a cylinder pivoted in said frame and a piston, and a common operating rod connected to said pistons and adapted to simultaneously move said pistons on corresponding strokes.

9. In a device of the character described, a plurality of pumps each supported for swinging movement and each having a cylinder and reciprocating piston, and means for simultaneously swinging said pumps in opposite directions about their pivots while 90 maintaining said pistons in unison on their compression strokes and on their other strokes.

ALEXANDER MARSCHALEK.
